UNITED STATES PATENT OFFICE.

ALBERT R. GOLDRICK, OF CLEVELAND, OHIO, ASSIGNOR TO CARL W. SCHAEFER, OF LAKEWOOD, OHIO.

METAL CASING FOR LEAF-SPRING COVERS.

Application filed January 10, 1922. Serial No. 528,332.

To all whom it may concern:

Be it known that I, ALBERT R. GOLDRICK, a citizen of the United States, residing at Cleveland, in the county of Cuyahoga and State of Ohio, have invented a certain new and useful Improvement in a Metal Casing for Leaf-Spring Covers, of which the following is a full, clear, and exact description, reference being had to the accompanying drawings.

This invention relates to protecting lubricant containing spring covers for laminated springs. It is concerned with that character of spring cover in which a container encloses the flexing portion of the spring. Where it is desirable to retain lubricant under pressure within the casing, it is necessary that it be manufactured economically and be easily applied; that it be durable in use and neat in appearance. In the making of such spring covers, it is preferable to use a fabric lubricant-impervious lining within the casing proper.

The objects of this invention include the construction of a casing of such a material which, when in position, will afford the necessary strength and flexible characteristics. A more specific object is to provide a means for securing the sheet in its position enclosing the spring with a minimum of effort, while answering the other requirements above outlined.

To this end, I choose to use a specially selected wire mesh or metallic fabric, cut in a certain fashion and supplied with specially designed securing devices as will be herein-after described in connection with the drawings. The essential characteristics are summarized in the claims.

In the drawing, Fig. 1 is an elevation of a spring having a cover embodying my invention secured thereto; Fig. 2 is a perspective view showing the cover having one form of securing means therefor; Fig. 3 is a transverse section showing a portion of the spring and cover; Figs. 4 and 5 are perspective views on an enlarged scale showing the casing as comprising two forms of woven screen; Fig. 6 is a perspective view showing a modification of the means for securing the casing around the spring.

In the various figures, I have shown my invention as attached to a cantilever spring, the leaves of which are anchored at C to a vehicle axle, and the top leaf of which, des-

ignated A, terminates in a shackle loop B. Surrounding the spring, intermediate the points of anchorage and shackle attachment, I have shown a cover which embodies a one-piece metallic casing 5 in close-fitting engagement with a fabric jacket 6. The construction of the casing, together with the means for securing it to the spring so as to provide, with the jacket, a fluid-tight pressure chamber for enabling the spring to be flexed without consequent loss of lubricant, constitutes an important feature of my invention; and the details of construction incidental thereto, will now be described.

The casing proper is constructed of woven material and is shown in two weaves as illustrated at 5 and 5^a respectively. This casing is adapted to be folded around three sides of the spring and to be so shaped that the ends overlap on the fourth side when the closure means, illustrated in Figs. 2 to 5, are employed. In this case each end is provided with a metallic strip or rail 8 which extends longitudinally of the casing. Each strip is shown as having a flange 8^a which may be rigidly secured to the screen as by brazing or soldering.

The means for locking the screen about the jacket as illustrated in Figs. 2 to 5 comprises a closure member 12 which is provided with inwardly extending flanges 12^a that are adapted to be substantially complementary to the flanges 8^a. When the flanges 12^a are formed, they are substantially in the position indicated in Fig. 4 so that the member 12 may be readily sprung over the strips 8 and thereafter pressed downwardly, as indicated in Figs. 2 and 3, thus locking the ends of the casing against the strip 10. In this way the fourth side of the spring is closed, and a lubricant-proof chamber extending substantially the entire length of the spring is secured.

As a further precaution for preventing lubricant from escaping between the jacket and spring, I may provide clamps 19 and 20 at the extreme ends of the casing, as indicated in Fig. 1.

To adapt a cover constructed according to my invention to high pressure systems of lubrication, I have shown a check valve 15 which is formed to receive the end of a grease gun. This valve communicates with the interior of the spring by reason of the fact that the threaded portion 15^a thereof is 119

in engagement with the nut 14, and lubricant is prevented from flowing outwardly along the threaded shank by reason of the cap washer 16 which abuts the outer side of 5 the metallic casing.

As a modification of the means for locking the ends of the casing around the spring, I have illustrated in Fig. 6 a construction which eliminates the necessity for the closure member. In this figure the locking is obtained by inter-engaging flanges 25 and 26 which are formed integrally with the ends of the casing 5. The preferred form of 10 constructing these flanges is to dip the ends of the casing in lead so as to form a strip extending longitudinally thereof a short distance inwardly, whereby one edge may be folded around the other to form an interlocking joint. Then after the edges are thus 15 interlocked, they may be permanently retained by soldering them together. A suitable way for accomplishing this would be to pass a soldering iron along the seam.

The method of assembling a spring cover 20 constructed in accordance with my invention is as follows: The jacket 6 having the nut 14 secured thereto is lapped around the spring to be covered, and the strip 10 is placed over the lapped edges of the jacket. 25 Then the casing of wire screen having the rails 8 secured to the ends thereof is folded around the jacket in such manner that the flanges 8^a are in upright position and adjacent the strip 10. This strip then, acts as a 30 bearing plate to prevent the fabric from being cut when the casing is locked around the spring. The rails are then locked by extending the flanges 12^a of the member 12 over the flanges 8^a, and then pressing or 35 hammering the flanges flat to the position indicated in Fig. 3. Then the lubricant valve 15 is threaded into the nut 14 and the clamps 19 and 20 are secured to the extreme 40 end of the casing, whereupon the spring is ready to receive lubricant under pressure. In case the locking means, illustrated in Fig. 6, is employed, the screen is previously 45 provided with the fusible metallic strip 25 and 26, and when the casing is placed around 50 the frame these strips are interlocked and then united.

An advantage of a spring cover constructed in accordance with my invention is that the necessity for separate encasing sections 55 is obviated, and accordingly the construction is greatly simplified. Furthermore, this form of casing is readily adapted for permitting the normal flexing operation of the spring without permitting lubricant held 60 under pressure to escape.

Having thus described my invention, I claim:

1. A spring cover comprising in combination a one-piece metallic casing formed of 65 wire screen and extending substantially the

entire length of the spring to be covered and joined longitudinally of the spring, metallic strips secured to the longitudinal edges of the screen and a longitudinally flanged strip engaging said strips secured to the screen and comprising a closure member for the casing. 70

2. In combination, a spring to be covered, a flexible jacket extending entirely around the spring, a one-piece screen casing surrounding the jacket and extending the entire length thereof, and means for locking the longitudinal edges of the screen, whereby a fluid-tight pressure chamber is formed 75 around the spring.

3. A spring cover comprising a one-piece metallic casing of woven material, said casing extending around three sides of the spring and on part of the fourth side, and means for interlocking the ends of the spring on the fourth side, whereby a fluid-tight pressure chamber is secured, said means comprising a pair of longitudinally flanged strips soldered to the edges of the screen on said fourth side of the spring and an interlocking member engaging said flanged strips. 80 90

4. A spring cover comprising in combination a fabric jacket entirely surrounding the spring to be covered, a metallic one-piece casing extending substantially the entire length of the spring and comprising woven wire screen closely embracing the jacket, and a replaceable member for entirely closing and locking the casing on the spring. 95

5. A spring cover comprising in combination, a spring, a fabric jacket lapped around the spring and longitudinally thereof, a metallic strip in engagement with the lapped edges of the jacket, a casing formed of woven wire and extending approximately entirely around the jacket and over said strip, and replaceable means adjacent said strip for locking the edges of the casing, whereby a fluid-tight pressure chamber is formed 100 around the spring. 105

6. In combination, a spring, a fabric jacket 110 extending entirely around the spring, a U-shaped woven metallic casing embracing the jacket on three sides thereof, with the free ends terminating short of each other adjacent the fourth side, a flanged metallic rail secured to each of the free ends of the casing, and a flanged closure member engaging the flanges of said rails to lock the casing about the jacket. 115

7. A spring cover comprising in combination, a spring, a flexible lubricant-proof jacket surrounding the spring, a woven metallic casing closely embracing the jacket, and a valve projecting laterally from the casing and providing communication with 120 the interior of the jacket. 125

In testimony whereof, I hereunto affix my signature.

ALBERT R. GOLDRICK.
